UNITED STATES PATENT OFFICE.

JOHN JOSEPH BERRIGAN, OF ORANGE, NEW JERSEY, ASSIGNOR TO FRANCIS J. AREND, OF NEW YORK, N. Y., AND JOHN BERNSTROM, OF STOCKHOLM, SWEDEN.

FEEDING DEVICE FOR CENTRIFUGAL MACHINES.

SPECIFICATION forming part of Letters Patent No. 685,320, dated October 29, 1901.

Application filed December 26, 1900. Serial No. 41,098. (No model.)

To all whom it may concern:

Be it known that I, JOHN JOSEPH BERRIGAN, of Orange, Essex county, New Jersey, have invented a new and useful Improvement in Feeding Devices for Centrifugal Machines, of which the following is a specification.

My invention is a device for feeding the material to be treated into a centrifugal machine.

My invention consists more particularly in the combination, with a rotary receptacle for the material to be treated having an inlet for said material at or near its axis of rotation, of a duct disposed within said vessel transversely said axis and communicating with said inlet and a device within said duct constructed to regulate the flow of material; also, in the combination, with a rotary receptacle for the material to be treated eccentrically placed with reference to its axis of rotation and provided with a feed-inlet, of a transverse duct receiving the material from said inlet, through which duct said material is projected by the action of centrifugal force against the wall of said vessel; also, in the combinations and mechanisms more particularly pointed out in the claims.

In the accompanying drawings, Figure 1 is a top view of a centrifugal machine containing my feeding device. Fig. 2 is a vertical section on the line 2 2 of Fig. 1.

Similar characters of reference indicate like parts.

For the purpose of illustrating my present device I have shown it embodied in the specific form of centrifugal machine which is disclosed in my application for Letters Patent, Serial No. 38,740, now pending.

The object of said machine is to separate solids from fluids and to deliver the solids in a substantially dry state.

1 is a standard.

2 is a cup integrally cast therewith.

3 is a hollow shaft passing through a gland 4 in the bottom of said cup. Said shaft 3 is rotated by any convenient means, and it carries on its upper end the drum 5. Within said drum 5 is eccentrically fixed the cylindrical receptacle 8 for the materials to be treated. The drum 5 is closed by a cover 9, 50 the flange 10 of which is internally threaded

to engage with a thread formed upon the drum-periphery. A gasket 11 may be interposed between cover and drum to make a tight joint. In the cover 9 is a central opening to receive the flanged plug 12, which supports the inlet-conduit 13. In the wall of receptacle 8 is an opening 18, communicating with the tapered conduit 19, formed in the plate 20, which extends between receptacle 8 and the smaller opening 21 in the wall of drum 5. The openings 18 and 21 and the conduct 19 together form an outlet for the separated solid constituent in receptacle 8.

In Fig. 1 is shown a top view of the detachable hood 22 for receiving said solid after ejection; but the presence of said hood is not necessary. In the bottom of receptacle 8 is a short pipe-section 26, through which the liquid constituent of the material under treatment escapes into the pan 6, which is within the cup 2. Said pan has a horizontal partition 7 with a central opening 14, through which the short pipe 26 passes.

31 is an escape-tube for the liquid entering pan 6. In the wall of receptacle 8 are openings 48 and 49 for allowing the liquid to flow between receptacle 8 and drum 5. The openings 50 in plate 20 serve to establish communication for the liquid within the drum from one side of plate 20 to the other.

Secured in any suitable way on the under side of the cover 9 is a plate 15, having a flange or wall 51, which is cut away at 52, Fig. 1. Journaled in the under side of this plate is a rotary cylinder 32, which has arms 33, which carry at their ends blades 34. When the cylinder 32 is rotated, these blades engage with the solid material deposited on that portion of the inner periphery of receptacle 8 to which it is delivered by the plate 15 and carry it to the outlet 18, as hereinafter described.

On the lower portion of the cylinder 32 is a gear 35, which engages with a gear 36 on the upper end of a shaft 37, which shaft passes through the hollow shaft 3 and is also to be provided with any suitable means for effecting its rotation. The pipe 38 serves to drain off any leakage which may enter cup 2.

I will now describe more particularly the 100

feeding device. The upper pivot of shaft 53 extends up through the bottom of plate 15 and carries the arms 54, 55, 56, and 57. The said arms in rotating sweep around in close proximity to the inner periphery of the curved portion 58 of the wall 51 of plate 15. The inlet-pipe 13 is so placed that it delivers all or the greater portion of the combined constituents to be separated into the space between the pivot 53 and the curved portion 58 of wall 51. Assume for the moment that the arms 54, 55, 56, 57 are not present. The material from the inlet-pipe 13 would then be thrown by centrifugal force of rotation from the edge 52 of plate 15 against the portion *a b* of the inner periphery of receptacle 8 which is directly opposite that edge. The liquid escaping through the openings 48 and 49 into the drum 5 forms a ring, the inner limit of which is indicated by the dotted circle shown in Fig. 1, and as the material is continuously supplied there is a continuous outflow of liquid through the pipe 26 into the pan 6, and so to the outlet-pipe 31. The solid material projected against the inner periphery of receptacle 8 is constantly removed by the blades 34, which carry it over the substantially dry surface within the receptacle 8 (represented by the arc c^{18} or d^{18} , Fig. 1) in accordance with the direction of movement of said blades, and so to the opening 18, out of which it is ejected by centrifugal force through the passage 19 and opening 21 in the wall of drum 5, whence it may immediately escape or pass into any suitable receptacle, such as the hood 22. Special attention is called to the fact that the plate 15 is a device for directing the material to be treated against a particular portion *a b* of the inner periphery of receptacle 8, this portion being in the apparatus here shown that most eccentric to the axis of rotation of drum 5. This arrangement of the plate 15 for directing the incoming material against the most eccentric portion of the inner periphery of the eccentrically-placed receptacle is a new feature in centrifugal machines. I have further found in practice that when the material is a fluid mass of combined solid and liquid it is especially advantageous to provide means for regulating the feed, and for this purpose the rotating arms 54, 55, 56, and 57 are provided. These arms are driven at a speed less than that of the rotary drum. Assuming them to be at rest and in the position represented in Fig. 1, they would then form a barrier to prevent the material lying in the quadrant *e*, between arms 54 and 55, and quadrant *f*, between arms 56 and 57, from being thrown from the plate 15 by the centrifugal force. If, however, the arms 54 are carried around in the direction of the arrow, then so much of the material as lies in the quadrant *f* will be permitted to escape and will be thrown by centrifugal force off of plate 15 as said quadrant 65 assumes the position *g*, or, in other words, each quadrantal space included between adjacent arms becomes filled with material, and

thus receives a definite quantity thereof, and these definite quantities are released and allowed successively to escape at the edge 52 of plate 15 as each quadrant in turn assumes the position *g*. The amount of material fed into the machine per given time will therefore depend upon the capacity of the quadrantal spaces between the arms 55, 56, &c., and the speed of revolution of said arms. The amount of material fed into the receptacle 8 may be proportioned to the capacity of the blades 34 for removing it from the place of deposit to the outlet, or, in other words, the amount of feed to the machine may be adjusted to its capacity for delivery either by suitably proportioning the feeding device with respect to the blades or the blades with respect to the feeding device and by adjusting the speed of travel of feeding device to blades, or vice versa. Thus in the specific embodiment of my invention here illustrated I show four arms with four quadrantal spaces between them. The delivery of this feeding device, therefore, for one revolution is equal to four times the amount of material which can be received in one of said quadrantal spaces. This then is the quantity of material which for one revolution of the arms will be projected against the inner periphery of receptacle 8. Now the arms 54, &c., are on the same shaft as the blades 34. Therefore one revolution of the arms 54 corresponds to one revolution of the blades 34. Therefore if the arms during one revolution cause a deposit of material measured, as aforesaid, the blades 34 should be so proportioned that during one revolution they shall be competent to collect and deliver that deposit to the escape-opening 18. Of course it is immaterial how many arms or blades are provided, so long as the aforesaid result is achieved. In Fig. 1 I show four arms 54, 55, &c., and five arms 33, carrying blades 34, and this arrangement, other things being equal, gives blades 34 the capacity to remove more material than the feeding-arms can supply, which may be desirable to avoid possibility of clogging; but of course I may have the blades 34 equal in number to the arms 54, 55, so that each blade may remove the amount of material deposited from one quadrantal space between said arms.

I claim—

1. In a centrifugal machine, a receptacle for the material to be treated eccentrically placed with reference to its axis of rotation and having an inlet for said material concentric with said axis, a support for said receptacle rotary on said axis and a duct disposed within said vessel and transversely said axis and communicating with said inlet; whereby the material entering said inlet and received in said transverse duct is projected from said duct against the inner peripherical wall of said receptacle by the action of centrifugal force due to the rotation of said receptacle.

2. In a centrifugal machine, a receptacle for the material to be treated eccentrically

placed with reference to its axis of rotation and having an inlet for said material concentric with said axis, a support for said receptacle rotary on said axis and a duct closed at 5 one end and open at the other disposed within said receptacle and transversely said axis and communicating with said inlet; the open end of said duct being located in proximity to the point of maximum eccentricity of the 10 inner peripheral wall of said receptacle, whereby the material entering said inlet and received in said duct is projected from said duct against said wall by the action of centrifugal force due to the rotation of said receptacle.

3. In a centrifugal machine, a rotary receptacle for the material to be treated having an inlet for said material concentric with its axis of rotation, a duct disposed within said 20 vessel transversely said axis and communicating with said inlet, and a device within said duct constructed to regulate the flow of the material passing through the same.

4. In a centrifugal machine, a rotary receptacle for the material to be treated having an inlet for said material concentric with its axis of rotation, a duct disposed within said vessel transversely said axis and communicating with said inlet, a rotary shaft passing 25 through said receptacle and entering said duct and a plurality of radial arms on said shaft within said duct; the said shaft being located so that radial arms on one side of the center thereof extend across the said inlet.

35 5. In a centrifugal machine, a rotary re-

ceptacle for the material to be treated, a duct therein constructed to receive the incoming feed and to direct the same against the inner circumferential periphery of said receptacle, a rotary shaft passing through the said 40 receptacle and into said duct, radial arms on said shaft within said duct and radial arms on said shaft outside of said duct and scrapers on said last-named arms constructed to remove the material deposited on said inner circumferential periphery.

6. In combination with the rotary receptacle 8 of a centrifugal machine having the axial inlet 13, the plate 15 having wall 51 and the cover 9 constructed and arranged to form a 50 radially-disposed duct within said receptacle, substantially as described.

7. In combination with the rotary vessel of a centrifugal machine having an axial inlet, a duct extending radially from said inlet to 55 the inner periphery of said vessel, and rotary arms as 54, 55, disposed within said duct, substantially as described.

8. In combination with the rotary receptacle 8 having an inlet, a duct extending radially from said inlet to the inner periphery of said vessel, a rotary shaft in said vessel and extending into said duct, an arm 54 on said shaft within said duct, and an arm 33 carrying a blade 34 on said shaft outside of 60 said duct, substantially as described.
